CART FOR TRANSPORTING CONTAINERS OR THE LIKE

Samuel Minchen, P.O. Box 932, Angleton, Tex. 77515

Filed Dec. 22, 1972, Ser. No. 317,629

Term of patent 14 years

Int. Cl. D12—02

U.S. Cl. D12—31

Fig. 2

Fig. 4

FIG. 1 is a right front perspective view of a cart for transporting containers or the like, showing my new design, it being understood that the broken lines are for illustrative purposes only;

FIG. 2 is a left side elevational view thereof;

FIG. 3 is a bottom plan view thereof; and

FIG. 4 is a rear elevational view thereof.

I claim:

The ornamental design for a cart for transporting containers or the like, substantially as shown.
